UNITED STATES PATENT OFFICE

150,578

DESIGN FOR AN AUTOMOBILE OR SIMILAR ARTICLE

Edward J. Kasnicka, Los Angeles, Calif.

Application July 6, 1946, Serial No. 131,346

Term of patent 3½ years

(Cl. D14—3)

To all whom it may concern:

Be it known that I, Edward J. Kasnicka, a citizen of the United States, residing in Los Angeles, in the county of Los Angeles, State of California, have invented a new, original, and ornamental Design for an Automobile or Similar Article, of which the following is a specification, reference being had to the accompanying drawings, forming a part thereof.

I claim:

The ornamental design for an automobile or similar article, as shown.

EDWARD J. KASNICKA.
